US00D542877S

(12) **United States Design Patent** (10) **Patent No.:** **US D542,877 S**
Murello et al. (45) **Date of Patent:** **** May 15, 2007**

(54) **COMPACT FIREARM**

(75) Inventors: **Johannes Murello**, Deisslingen (DE);
Wilhelm Fischbach,
Deisslingen-Laufen (DE); **Thomas Schweikart**, Vöhringen (DE);
Alexander Stumpf, Bitz (DE)

(73) Assignee: **Heckler & Koch, GmbH** (DE)

(**) Term: **14 Years**

(21) Appl. No.: **29/230,459**

(22) Filed: **May 20, 2005**
